US00D559181S

(12) **United States Design Patent** (10) Patent No.: **US D559,181 S**
Yan (45) Date of Patent: **** Jan. 8, 2008**

(54) **BATTERY CONNECTOR**

(75) Inventor: **Lai Ming Yan**, Tu-Cheng (TW)

(73) Assignee: **Cheng Uei Precision Industry Co., Ltd.**, Taipei Hsien (TW)

(**) Term: **14 Years**

(21) Appl. No.: **29/272,743**

(22) Filed: **Feb. 16, 2007**

(51) LOC (8) Cl. **13-03**

(52) U.S. Cl. **D13/120; D13/147**

(58) Field of Classification Search **D13/120, D13/133, 146-147, 184, 199; 439/108, 577, 439/630, 660, 680, 773, 862**

See application file for complete search history.

CLAIM

The ornamental design for a battery connector, as shown and described.

DESCRIPTION

FIG. 1 is a perspective view of a battery connector showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing is included for the purpose of illustrating environmental features and forms no part of the claimed design.
